[57] ABSTRACT

A substantially full opening tear-open closure for a container, the closure being of the type having an endless thin wall portion intermediate a removable panel and a residual rim. The outside surface of the thin wall portion is recessed from the adjacent outside surface of the rim, and a smooth endless residual edge is disposed at the intersection of the outside surface of the rim and the adjacent surface intermediate the rim and the thin wall portion. The thin wall portion and its endless junctures with both the rim and the removable panel are configured to form a predetermined continuous line-of-weakening which is wholly disposed nearer the wall of the container body to which the closure is secured than the smooth endless residual edge. Thus, upon tearing along the predetermined line-of-weakening to effect the removal of the removable panel, the raw edge formed thereby is also wholly under the residual rim whereby the raw edge is substantially precluded from being a cut hazard.

TEAR-OPEN CLOSURE

CROSS REFERENCE TO RELATED APPLICATION

This application is related to the commonly assigned concurrently filed application of Charles D. Stuard entitled A METHOD OF MAKING A TEAR-OPEN CLOSURE filed Mar. 27, 1972, Ser. No. 238,074 which discloses and claims a method of making the instant invention.

FIELD OF THE INVENTION

This invention relates generally to providing tear-open closures having an integral rim around a removable panel wherein a predetermined line-of-weakening is formed therebetween.

BACKGROUND OF THE INVENTION

End closures for tubular containers commonly have a U-shape rim forming a peripheral channel which is adapted to receive the end of a tubular container body and to be secured thereto by crimping, rolling, gluing, or the like.

A number of such closures have been devised which incorporate tear-open means such as a pull tab secured to a removable panel, the removable panel being defined by a circularly extending endless line-of-weakening formed, for instance, by a score line. In order to provide a large dispensing aperture in such closures, to facilitate passage of commodities or fingers or the like therethrough, the line-of-weakening is generally disposed in the disc-shape central portion of the closure close to the inner chime wall of its U-shape rim. Thus, the dispensing aperture can be almost as large as the bore of the tubular container body.

Freshness preserving characteristics and cost of such closures are often critical. Also, appearance, convenience, and consumer safety are important considerations. In general, closures formed of metal are adequate, and in some respects, such as cost and freshness preserving, are sometimes superior to closures fabricated from other materials.

However, upon opening such end closures, particularly sheet metal closures, the raw edge formed by tearing along the line-of-weakening frequently becomes a cut hazard. That is, a circularly extending raw edge around a dispensing aperture through which a consumer's hand or fingers may be extended has too often resulted in a cut, scrape, or contusion. The present invention is addressed to providing a suitable closure of the general type delineated hereinabove wherein the cut hazard has been substantially eliminated.

Of course, others have recognized the cut hazard precipitated by tear-open containers and have devised closure configurations directed to that end. For instance, U.S. Pat. No. 3,601,279 issued Aug. 24, 1971 to David C. O'Neill discloses a score line having a radius along at least one edge of the bottom wall thereof to insure tearing along a predetermined portion of the score line to reduce the cut hazard around a dispensing opening. Some other representative approaches to eliminating the cut hazard are disclosed in: U.S. Pat. No. 3,543,961 issued December 1970 to James E. Kennedy and James R. Pound; U.S. Pat. No. 3,557,997 issued Jan. 26, 1971 to Thomas R. Stanley; U.S. Pat. No. 3,447,713 issued June 3, 1969 to Frederick J. Stec;

U.S. Pat. No. 3,527,377 issued Sept. 8, 1970 to E. E. Colby et al; and U.S. Pat. No. 3,195,764 issued July 20, 1965 to L. Fried et al. However, none of these approaches has solved all of the problems associated with tear-open closures in the manner of nor to the degree of the present invention.

For instance, the end closure configuration disclosed by Kennedy and Pound in U.S. Pat. No. 3,543,961 has a line-of-weakening formed by a score line having side

walls extending from its inside surface towards its outside surface at the convex juncture of the inner chime wall and the removable central panel. Thus, the line-of-weakening is near the inside surface of the container body when the closure is assembled thereto. Such a score line can be formed after the inner chime wall has been substantially fully formed. However, when the removable panel is removed, the raw edge formed at the base of the inner chime wall is not wholly disposed under and radially outward from the contiguous portion of the inner chime wall. That is, the raw edge is not closer to the container wall than the contiguous portion of the inner chime wall.

SUMMARY OF THE INVENTION

The nature and substance of the invention will be more readily appreciated after giving consideration to its major aims and purposes. The principal objects of the invention are recited in the ensuing paragraphs in order to provide a better appreciation of its important aspects prior to describing the details of a preferred embodiment in later portions of this description.

A major object of the invention is providing a tear-open closure for a container wherein a predetermined line-of-weakening is nearer the side wall of the container than the smooth residual edge of the closure adjacent the predetermined line-of-weakening.

Another object of the invention is providing a tear-open sheet metal end closure for a tubular container, the closure having a peripherally extending rim spaced from a removable panel by an endless thin wall portion recessed from the outwardly facing surface of the rim.

These and other objects are achieved by providing a substantially full opening tear-open closure for a tubular container comprising a removable panel, means for removing the removable panel, an integral rim extending around the periphery of the removable panel, and an endless thin wall portion intermediate the removable panel and the rim. The endless thin wall portion forms a predetermined line-of-weakening intermediate the removable panel and the rim. The outside surface of the thin wall portion is recessed from the outside surface of the rim and is disposed so that the predetermined line-of-weakening is nearer to the wall of the container than the smooth residual edge of the closure at the intersection of the outside surface of the rim and the surface of the closure extending from the outside surface of the rim to the outside surface of the thin wall portion. The rim is configured to be secured to a tubular container so that the rim is substantially precluded from bending inwardly from the wall of the container upon removal of the removable panel. Therefore, the raw edge formed by tearing the closure along the predetermined line-of-weakening to remove the removable panel to open the container will remain nearer the wall of the container and under the adjacent smooth residual edge of the rim.

BRIEF DESCRIPTION OF THE DRAWINGS

While the specification concludes with claims particularly pointing out and distinctly claiming the subject matter regarded as forming the present invention, it is believed the invention will be better understood from the following description taken in connection with the accompanying drawings in which:

FIG. 1 is a fragmentary perspective view of the top of a tubular container having a preferred tear-open closure embodiment of the present invention.

FIG. 2 is an enlarged fragmentary sectional view through the rim of the tubular container of FIG. 1 taken along line 2-2 thereof.

FIG. 3 is a fragmentary sectional view of the container rim of FIG. 2 after a substantially full-open dispensing aperture has been opened in the container by removing the removable panel from the preferred closure embodiment of the instant invention.

FIG. 4 is a fragmentary sectional view of the rim of a container similar to the container shown in FIG. 2 but which comprises an alternate closure embodiment of the instant invention having an alternate line-of-weakening configuration.

DESCRIPTION OF THE PREFERRED EMBODIMENT

Container 20, FIG. 1, comprises tubular container body having a wall 21, and a closure 22 having a tear-tab 23. Although wall 21 is shown to have a right circular cylindrical geometry and tear-tab 23 is of the ring type, it is not intended to thereby limit the instant invention.

Closure 22, FIG. 2, a preferred embodiment of the instant invention, comprises a disc shaped removable panel 26 having a U-shape rim 24 integrally formed thereon with a predetermined line-of-weakening defined by, for example, score line 25 disposed therebetween. However, it is not intended to limit the present invention to a line-of-weakening formed by a score line. Although the geometry and disposition of the thin wall portion designated 42 and its junctures with rim 24 and removable panel 26 are critical to the present invention as hereinafter set forth, the manner of producing the thin wall portion is not believed to be critical to the present invention.

Closure 22 has an outside surface 28 and an inside surface 29. Rim 24 comprises an inner chime wall 30 and an outer chime wall 31 both of which, in the preferred embodiment of the instant invention, are substantially right circular cylindrical in form. The radially outwardly facing surface 32 of inner chime wall 30 is spaced from the radially inwardly facing surface 33 of outer chime wall 31 to form a U-shape cross section, peripherally extending channel therebetween for receiving an end of wall 21. A circumferentially extending fillet 34 is formed at the juncture of inner chime wall 30 with removable panel 26. Score line 25 depressed or recessed from the outside surface 28 of closure 22, comprises a circularly extending radially outwardly canted, radially outermost wall 38, a circularly extending, radially outwardly canted, radially innermost wall 39, and a bottom wall 40. The circularly extending intersection of wall 38 with the adjacent outside surface 28 of inner chime wall 30 is a circularly extending smooth edge which is hereby designated

residual edge 41. As will hereinafter be delineated, residual edge 41 is furtherest removed from the wall 21 after the closure 22 has been opened by removing panel 26. The material between the bottom wall 40 and the adjacent inside surface 29 of fillet 34 is of relatively thin cross-section and will be designated as the thin wall portion 42. As is well known to those having ordinary skill in the art, the thickness of the thin wall portion 42, relative to the thickness of the other portions of tear-open closures, defines a line-of-weakening which is relatively easily torn to remove the central portion of the closure adjacent the line-of-weakening.

Score line 25, as shown in FIG. 2, has relatively sharp (unrounded) peripherally extending corners 43, 44. Both corners 43, 44 of the score line are radially outwardly disposed from residual edge 41 because of the radially outwardly canted geometry of score line 25 with respect to the central axis of the container 20. That is, corner 43 is a distance Δr_1 radially outwardly from residual edge 41, and corner 44 is a distance Δr_2 radially outwardly from residual edge 41. As is well known to those having ordinary skill in the art, tearing will be initiated at either of the sharp corners 43 or 44, or at a point intermediate thereof through the thin wall portion 42. This insures that the raw edge 45, FIG. 3, formed by tearing along the line-of-weakening will always be disposed nearer the wall 21 of the container 20 than the smooth residual edge 41.

Closures 22 as described are preferably composed of a relatively hard temper sheet metal. For instance, 5052-H19 aluminum having a thickness of from about six to about twelve thousandths of an inch but preferably about eight thousandths of an inch has been widely adopted for tear-open canned beer and beverage closures. In such closures, this wall portion 42 is commonly from about two to about four thousandths of an inch thick. However, it is not intended to limit the present invention to metal closures of this temper or of these dimensions.

Referring back to FIG. 2, closure 22 is applied to wall 21 to form container 20 by telescoping the end of wall 21 into the U-shape rim of closure 22 and providing an adhesive 96 to bond them together and to fill the space therebetween. Adhesive 96 may be placed in the channel of rim 24 before the end wall 21 is telescoped thereinto whereby the end of wall 21 displaces some of the adhesive forming a bead thereof intermediate the radially inwardly facing wall 21 of container 20 and fillet 34 of the closure. Alternatively, a bead of adhesive may be placed on the edge of wall 21 before it is telescoped into the U-shape rim of the closure. Insofar as the present invention is concerned, securing the closure to the wall of the body of the container through the use of adhesives, or rolling, or otherwise is only necessary to prevent the base of the inner chime wall 30 from bending so far inwardly upon removal of panel 26 as to position raw edge 45, FIG. 3, further from container wall 21 than residual edge 41.

At some point in the fabrication of container 20, tear-tab 23 must be secured to removable panel 26 through the use of an integral rivet, or a discrete rivet, or otherwise so that the predetermined line-of-weakening defined by score line 25 or otherwise can be wholly ruptured by pulling on tear-tab 23. Thus, upon removal of removable panel 26 from the container, an aperture

is opened in the end of container 20 which is substantially as large as the inside of wall 21 of container 20. Therefore, closure 22 is designated a substantially full opening tear-open closure.

Referring now to FIG. 3, the fragmentary portion of container 20 of FIG. 2 is shown after the removal of removable panel 26 as by pulling on tear-tab 23, FIG. 1. FIG. 3 further shows that raw edge 45 formed by tearing along the predetermined line-of-weakening is wholly disposed radially outwardly from the residual edge 41 of the inner chime wall. Because raw edge 45 is wholly disposed under and radially outwardly from the smooth residual edge 41, the cut hazard commonly associated with tear-open containers is substantially obviated.

Although the preferred configuration closure 22 is circular, the present invention can be utilized to form polygonal closures having rounded corners, oval closures, and other closures having continuously curved lineaments. Also, although removable panel 26 of closure 22 is described as being planar, embossments and the like are not summarily precluded from closures embodying the present invention.

An alternate configuration closure 22a is shown in FIG. 4. This alternate configuration closure also has a thin wall portion 42 formed by a radially outwardly canted score line which is designated 25a. However score line 25a of the alternate configuration is shown to have only one sharp corner 44a and one rounded corner 43a. A score line having one sharp corner and one rounded corner is disclosed in a planar blank in U.S. Pat. No. 3,691,279 issued Aug. 24, 1971 to David C. O'Neill.

In removing the central panel 26 from the closure 22a, FIG. 4, the thin wall portion 42 will tear through the thin wall portion 42 along the sharp internal, circularly extending corner 44a of radially outwardly canted score line 25a. This forms a raw edge that is wholly disposed radially outwardly from residual edge 41 of closure 22a. That is, the raw edge is closer to wall 21 of container 20 than residual edge 41, thus providing the same cut hazard protection as the preferred embodiment closure 22.

While particular embodiments of the present invention have been illustrated and described, it will be obvious to those skilled in the art that various changes and modifications can be made without departing from the spirit and scope of the invention and it is intended to cover in the appended claims all such changes and modifications that are within the scope of this invention.

What is claimed is:

1. A tear-open closure for a container, said closure comprising a removable panel, an integral rim extending peripherally around said removable panel, and means for removal of said removable panel, said means for removal of said removable panel comprising an endless thin wall portion intermediate said removable panel and said rim, said thin wall portion having its outside surface recessed from the outside surface of said rim, said closure further comprising a wall surface intermediate the outside surface of said rim and the outside surface of said thin wall portion, and a smooth residual edge at the intersection of the outside surface of said rim and said wall surface, said thin wall portion

and its junctures with said rim and said removable panel being configured and disposed to define an endless predetermined line-of-weakening which is nearer the side wall of the container than said smooth residual edge.

2. The closure of claim 1 wherein said rim comprises a tubular inner chime wall extending upwardly from the periphery of said removable panel.

3. The closure of claim 1 fabricated of sheet metal having a thickness of from about six-thousandths to about twelve-thousandths of an inch wherein the thickness of said thin wall portion is from about two-thousandths to about four-thousandths of an inch.

4. The closure of claim 1 fabricated of 5052-H19 aluminum having a nominal thickness of about eight-thousandths of an inch and wherein said thin wall portion has a thickness of from about two-thousandths to about four-thousandths of an inch.

5. The closure of claim 4 wherein said rim has a U-shape cross section comprising an inner chime wall spaced from an outer chime wall forming a U-shape channel therebetween, said channel being adapted to receive a tubular wall of a container and to have said rim secured to the tubular wall of the container whereby deformation of said rim by the removal of said removable panel is substantially precluded so that the raw edge formed by the removal of said removable panel remains nearer the adjacent wall of the container than said smooth residual edge.

6. A tear-open container comprising a wall having a dispensing opening therein, and a tear-open closure, said closure comprising a removable panel, an integral rim extending peripherally around said removable

panel, and means for removal of said removable panel, said means for removal of said removable panel comprising an endless thin wall portion intermediate said removable panel and said rim, said thin wall portion having its outside surface recessed from the outside surface of said rim, said closure further comprising a wall surface intermediate the outside surface of said rim and the outside surface of said thin wall portion, and a smooth residual edge at the intersection of the outside surface of said rim and said wall surface, said thin wall and its junctures with said rim and said removable panel being configured and disposed to define an endless predetermined line-of-weakening which is nearer the side wall of the container than said smooth residual edge.

7. The tear-open container of claim 6 wherein said closure comprises sheet metal having a thickness of from about six-thousandths to about twelve-thousandths of an inch wherein the thickness of said thin wall portion is from about two-thousandths to about four-thousandths of an inch.

8. The tear-open container of claim 7 wherein said rim has a U-shape cross section comprising an inner chime wall spaced from an outer forming wall forming a U-shape channel therebetween said channel being adapted to receive a tubular wall of a container and to have said rim secured to the tubular wall of the container whereby deformation of said rim by the removal of said removable panel is substantially precluded so that the raw edge formed by the removal of said removable panel remains nearer the adjacent wall of the container than said smooth residual edge.

9. The tear-open container of claim 8 wherein said closure is fabricated of 5052—H19 aluminum having a nominal thickness of about eighth-thousandths of an inch and wherein said thin wall portion has a thickness of from about two-thousandths to about four-thousandths of an inch. 5
